CLAIM

The ornamental design of a handle for cooking utensils, as shown and described.

DESCRIPTION

FIG. 1 is a perspective view of a handle for cooking utensils showing my new design;

FIG. 2 is a front elevational view thereof;

FIG. 3 is a left side elevational view thereof the right side being a mirror image of the left side;

FIG. 4 is a rear elevational view thereof;

FIG. 5 is a top plan view thereof; and,

FIG. 6 is a bottom plan view thereof.

The broken line showing of a spatula in FIGS. 1-6 is for illustrative purposes only and forms no part of the claimed design.
